(57) **CLAIM**

The ornamental design for a portable ducting kit, as shown and described herein.

DESCRIPTION

FIG. 1 is a perspective view of the portable ducting kit showing a flexible tubing within a casing.

FIG. 2 is a front view of the portable ducting kit shown in FIG. 1.

FIG. 3 is a right side view of the rear portion of the portable ducting kit of FIG. 1, with the rear portion shown separated from the casing.

FIG. 4 is a top perspective view of the front portion of the portable ducting kit of FIG. 1, with the front portion shown separated from the casing and the flexible tubing extended to more clearly show the form of this portion.

FIG. 5 is a detailed view of the rear end of the portable ducting kit shown separated from the casing and flexible tubing.

FIG. 6 is a detailed view of the front end of the portable ducting kit shown separated from the casing and flexible tubing; and,

FIG. 7 is a side view of the portable ducting kit of FIG. 1. The features shown in broken lines in the drawing figures depict environmental subject matter only and form no part of the claimed design.
